Application November 14, 1947, Serial No. 785,858

14 Claims. (Cl. 101—186)

1

This invention relates to improvements in methods of and apparatus for printing multicolor pictures or designs upon a continuous strip of fabric or other suitable material, and has particular reference to a method and apparatus as described wherein the fabric to be imprinted is mounted upon a carrier which moves along the frame or base of the apparatus and brings a portion of the fabric into contact with printing plates to imprint particular colors in successive order. This permits the fabric to be automatically retracted and brings same into proper alignment and register with each successive printing plate.

As the carrier advances along the frame during the operation of the apparatus, a section of the fabric makes a rolling contact with the first printing plate and has imprinted thereon the first color of the required group of colors. After the first impression is made the roller contact with the printing plate is broken and allows the fabric to be retracted, relatively with the first printing plate. The carrier, continuing its forward movement brings the portion of the fabric to be imprinted into contact with the next or succeeding printing plate and automatically registers the fabric with same. The fabric is then given a roller contact with the second printing plate and receives an impression of a different color and after passing said second printing plate the fabric is again retracted and moved forward into register with a third printing plate to receive a third color impression and so on over a multiplicity of printing plates each printing a section of a different color until the multicolor design is completed.

When the carrier has reached the end of its stroke or movement the fabric is again retracted and the carrier automatically comes to a stop and sets in motion a means to lower a bed carrying the aforesaid printing plates to a predetermined level at which point a means is set in motion to move a series of various colored inking rollers over the said lowered printing plates. After passing over the said printing plates the inking rollers are retracted and as they are retracted they again move over the said printing plates and continue their movement until they are fully retracted whereupon a means is set in motion to retract the carrier and return it to its starting position. When the carrier reaches the said starting point a means is set in motion to raise the aforesaid bed carrying the said printing plates upwardly to its normal printing position. When the said bed reaches its said uppermost

2

position a means is set in motion to move a succeeding portion of fabric into position for printing another multicolor design.

Various mechanical means may be employed to accomplish the successive operations above described as for instance:

1. Numerous gears, cams and clutches may be employed to accomplish the successive movements of the operation;

2. Pneumatic or hydraulic means may be incorporated to achieve the desired result, or

3. A multiplicity of electrically driven motors may be used to give the various successive movements to the parts wherein the action of the various driving motors is controlled or regulated by a series of switches and relays.

In the embodiment herewith shown and described electric motors are employed which are controlled by means of "make" and "break" electric switches operated by contact with a moving part or by solenoids and relays interposed in certain circuits and actuated by means of a moving part of the apparatus.

One object of this invention is to provide in 25 a method and apparatus as described, means for locking the fabric in a predetermined position and keeping same in said fixed position during its printing and retracting movements.

Another object of this invention is the provision therein of a means for releasing the said fabric from its locked position during the winding up process to bring another section of the fabric into position for imprinting.

A further object of this invention is the inclusion therein of a means for coating the surface from which an imprint is to be taken with a suitable chemical fluid which will prepare the said printing surface to receive the colored inks imprinted thereon.

A further object of this invention is the provision therein of removable ink trays or containers for carrying the variously colored inks.

A still further object of this invention is the inclusion therein of reciprocally moving roller frames and rollers for inking the said printing plates.

A further object of this invention is the inclusion therein of means for periodically lowering a bed carrying the said printing plates to allow the said inking rollers to engage upon the plates and raising the said bed after the inking rollers are retracted.

A further object of this invention is the inclusion therein of a means for measuring a predetermined length of fabric which is to be im-

printed and intermittently moved through the apparatus.

Another object of this invention is the inclusion herein of cam means to lift the inking rollers over and clear of certain parts of the bed carrying the printing plates to avoid depositing ink upon said parts.

A still further object of this invention is the provision of an organization in which the constituent elements are so arranged structurally and functionally as to assure improved results with materials and members which may be manufactured at reasonable cost, may be easily assembled and which will be efficient in operation with minimum wear to the parts.

The invention possesses other objects and features of advantage some of which, with the foregoing, will be set forth in the following description and in the claims wherein parts will be identified by specific names for convenience, but they are intended to be as generic in their application to similar parts as the art will permit. In the accompanying drawings there has been illustrated the best embodiment of the invention known to us, but such embodiment is to be regarded as typical only of many possible embodiments, and the invention is not to be limited thereto.

The novel features considered characteristic of our invention are set forth with particularity in the appended claims. The invention itself, however, both as to its organization and its method of operation, together with additional objects and advantages thereof, will best be understood from the following description of a specific embodiment when read in connection with the accompanying drawings, in which:

Figure 1 is a side elevation of an apparatus employed in the embodiment herein set forth, and having parts broken away.

Figure 2 is a plan or top view with portions broken away.

Figure 3 is an end elevation of a part showing one of the driving means.

Figure 4 is an end elevation looking into the direction indicated by the arrow X of Figure 2.

Figure 5 is an elevational view of the opposite end.

Fig. 5a is an enlarged sectional detail of a part which will be hereinafter described.

Figure 6 is an enlarged detail of a part which will be hereinafter explained.

Figure 7 is a fragmentary side elevational view of the apparatus showing a portion in section and parts broken away.

Figure 8 is an enlarged fragmentary sectional view of a detail which will be hereinafter explained.

Figure 9 is a sectional plan view of same taken along line 9—9 of Figure 8.

Figure 10 is a sectional elevational view taken along line 10—10 of Figure 9.

Figure 11 is a diagram showing the electrical circuits and controlling switches.

Referring in detail to the parts 11 designates the main frame or supporting structure of the apparatus, 12 is an auxiliary frame extending laterally from one side of the said main frame, along a part of its length. A carrier 13, is slidably mounted upon the top of the said main frame 11 and is provided with wheels 14 which move in grooves or tracks 15. The carrier 13 is formed with the upright side members 16 and 17 which are held together by cross-rods 18 secured to the said side members in any suitable manner. A

series of rollers are mounted between the said side members 16 and 17 and comprise a roller 19 which carries the fabric 20, a roller 21 around which the fabric 20 passes to receive a coating fluid, over and partially around a roller 22 downwardly to and partially around and between rollers 23 and 24, thence to and partially around a print contacting roller 25, from whence the fabric passes to and partially around and between a heating roller 26 and a roller 27 on to a pickup roller 28 upon which the fabric is finally wound after receiving various color impressions.

The said rollers 23 and 24 are mounted in a frame 29 which is in turn slidably mounted upon the side members 16 and 17 of the carrier 13. The said frame 29 slides in a slot 30 upon each side member of the carrier. A second frame 31 slidably in a slot 32 upon each side member 16 and 17 carries the heater roller 26 and its adjacent contacting roller 27 and is connected with the frame 29 by means of a flexible band 33 which passes over a pulley 34 upon each side member of the said carrier. A spring 35 is secured at one end to a post 36 upon the side member and at its other end to a pin 37 upon the frame 29 and acts to keep the frame 29 normally in its raised position (Figure 1) and its connected frame 31 in its lowermost position.

The fabric 20 is normally held immovable between the rollers 23 and 24 and between the heater roller 26 and its adjacent contacting roller 27 by means of clamping wedge shaped members 38 and 39 respectively which are normally held tightly against the fabric (Figures 1, 6 and 7) by means of springs 40 engaging against arms 41. Arms 42, integral with the said arms 41 carry the said wedge shaped members 38 and 39 which extend across the width of the said carrier between the said upright members 16 and 17 (Figures 4 and 5). Solenoids 43, whose cores 44 engage the arms 41 are adapted to push said arms 41 against the springs 40 to move the arms 42 out and disengage the said wedges 38—39 thereby freeing the fabric, when the said solenoids are electrically energized.

45 A trough 44 attached upon the carrier 13, is fixed between the side members 16 and 17 and employed to hold a chemically prepared fluid specially adapted for surface coating the fabric as it passes around the roller 21. For this purpose 50 a roller brush 45, rotated by means of a belt and pulley connection 46 with the roller 21, is mounted in the said trough and applies the said fluid to one side of the fabric (Figure 1).

The carrier 13, as hereinbefore stated, is moved forward along the length of the supporting frame 11, to the position shown by the dot-dash lines in Figure 1 and is subsequently retracted or brought back to its starting position as shown by the full lines of Figure 1. This reciprocating movement is accomplished by means of a threaded driving shaft 47, one on each side of carrier 13, rotatively mounted in bearing brackets 48, and 49 attached to the supporting frame 11. Both shafts 47 have a threaded engagement with a bracketed bearing arm 50 secured upon each side member of the carrier 13 and are rotated by worm gear connections 51 and 52, shaft 53, gears 54 and 55 and motor 56. The said motor shaft 56 and gears have been omitted from Figure 4 for better illustrating purposes but are clearly shown in Figures 1, 2 and 3. Electric switches which are automatically operated control the forward and backward movements of the carrier 13 as 70 75 will be hereinafter more fully described.

A printing bed 57 is vertically movable in the supporting frame 11 and is guided in its vertical movements by strips 58 upon the said supporting frame which engage conforming slots 59 in the said printing bed 57 (Figures 2 and 5). Vertical movement is imparted to the said printing bed by means of threaded supporting rods 60 arranged in pairs (best shown in Figures 4 and 5), and engaging, at their lower ends, through bores 61 and 62 in a cross brace 63 and through a worm gear 64 which is internally threaded to engage the threaded portion of the rods 60. A complementary worm gear 65 engages between and with each gear 64 and is rotated by a shaft 66 to which the said worm gear 65 is attached. A motor, 67, electrically driven and having a speed reducing mechanism 68 drives the shaft 66 to lower or raise the said printing bed 57. The electrical energy to operate the said motor 67 is automatically controlled by switches and will be herein-after fully explained.

Resting upon the printing bed 57 and held thereon by the side strap members 69 (Figure 2) are a series of printing plates 70 (five in number in the embodiment here shown and described) each plate carrying a different color design which is successively imprinted upon the fabric 20 to form a complete multicolor design.

The aforesaid laterally extending auxiliary frame 12 has slidably mounted upon it, a series of blocks 71 carrying, pivotally attached thereto as at 72, arms 73 having fork shaped ends 74. Inking rollers 75 are rotatively carried upon the forked ends 74 and have roller engagement with ink transferring rollers 76 which in turn pick up ink from the contacting rollers 77. The said rollers 77 take up ink from a tray or trough 78 (Figures 4, 5 and 10). Racks 79 attached to the underside of each of said blocks 71, which carry the inking mechanisms described, engage gears 80 fixed upon a shaft 81 extending from side to side of the laterally extending frame 12. The said shaft 81 is rotated at proper intervals by an electrically driven motor 82 and geared reducing mechanism 83 and the operation of the said motor is controlled by automatically actuated switches as will be hereinafter described.

At proper intervals, that is, when the printing bed 57 is in its lowermost position (dot-dash lines in Figure 5) the inking rollers 75 are moved inwardly to contact the upper or printing surface of the printing plates 70 and deposit ink thereon and are immediately retracted to their inoperative position. When the inking mechanism moves in and withdraws from the printing plates 70 the inking rollers 75 are raised as they pass over the aforementioned strap members 69 to avoid depositing ink thereon. To accomplish this cams 84 are formed upon the auxiliary frame 12 which are engaged by followers 85 formed upon the forked ends 74 of the arms 73. As the followers 85 pass over the cams 84 the inking rollers 75 are raised and held in raised position until they have passed the said strap members 69.

The rollers 77 rotate in each of the said troughs 78 and are mounted upon a shaft 86 which is given rotary motion by means of a motor 87 connected to the shaft 86 by means of a reducing gear mechanism 88.

The aforesaid ink roller carrying arms 73 are formed with slots 89 through which a weighted member 90 is adapted to slidably engage and may be secured in any desired position by means of wing nuts 91. The said wing nuts 91 are formed with depending, threaded bolts 91a which

engage through the said weighted members 90, through said slots 89 in the arms 73, through threaded plates 91b and lock nuts 91c (see Fig. 5a). Upon loosening the said lock nuts 91c and plates 91b, the weighted members 90 may be moved along the said arms 73 and upon tightening the plates 91b and lock nuts 91c the said weighted members 90 may be securely fixed in any desired position upon the said arms 73.

10 Resting members 92 are formed upon the sliding inking blocks 71 and function to hold the arms 73 in proper position when the cam followers 85 move away from the cams 84.

The arms 73 may be swung upwardly as indicated by the dot-dash lines in Figure 5 to allow access to the ink troughs or trays 78. The said ink troughs or trays 78 are held in a raised position upon cams 93 (Figures 8, 9 and 10), which when turned as indicated at 93' bring the bottom of the ink troughs down to the level of a shelf 94 from which position they may be manually removed.

The cams 93 are keyed upon a shaft 95 to one end of which a lever handle 96 is attached and affords a means to rotate the said cams 93 to lower the troughs 78 for removal from the apparatus or raise same to their upper operating position. When the cams are turned to raise the said troughs the handles 96 are in an upright position and may be so held by a sliding bolt 97 having a socket end 98 which engages over the end of said handle. The aforementioned sliding block 71 moves in a groove 99 formed by a bar 100 which is suitably attached to the top of the said laterally extending supporting frame 12.

When the carrier 13 starts its movement forward or in the direction indicated by the arrow Y on Figure 1, the roller 25 carrying the fabric around it will contact the strap member 69 and will turn as it rolls over the said strap member. The frictional contact between the roller 25 and the strap member 69 will cause the said roller to turn and unroll the fabric 20 over the first printing plate 70 to receive an impression therefrom.

40 At the same time the frame 29, to which the fabric is locked by means of the wedge clamp 38, is drawn down against the pressure of the spring 35 and draws up the frame 31 which is tied to the said frame 29 by means of the flexible band 33.

The fabric 20 being locked to the said frame 31 by means of the locking clamp 39 moves up in the slot 32 as indicated in Figure 7. The roller 25 as shown in Figure 7 having reached the end 55 of the strap 69 rides free of same and reaches the gap between the said first printing plate and the second or succeeding printing plate and its strap member, releasing the frictional pressure and allowing the spring 35 to snap the frame 29 back to its starting or uppermost position and allowing the frame 31 to drop to its lowermost position as shown in Figure 1. At the same time the fabric 20 is brought back to its original position and ready for an impression from the second printing plate.

The cycle of operation just mentioned is repeated, as the carrier moves forward, until all of the printing plates have received their color impressions and the carrier has reached the end of its run by the dot-dash lines in Figure 1. The position of the frames 29 and 31 on the carrier being as shown by the full lines in Figure 1. At this point the carrier stops and the bed 57 begins to descend and when same reach their lowermost position the printing rollers move in over the

lowered printing plates 70, are retracted and when fully retracted the carrier starts its retraction movement.

When the carrier is fully retracted the bed 57 rises to its uppermost level upon reaching which the wedge clamps 38 and 39 are released, to free the fabric, a motor 101 is actuated and winds a portion of fabric equivalent to a section required for each printing, the motor 101 stops and the wedge clamps 38 and 39 again come into action to lock the section of fabric to be imprinted in fixed position and the carrier again starts forward repeating the cycle of operations above described.

Referring to Figures 4, 5 and 6 of the drawings 102 indicates a measuring device of standard type which controls an electric circuit to start and stop the motor 101 at proper intervals. In Figure 1, 103 indicates a connection box having a flexible conductor 104 leading to any suitable connection box remote from the apparatus while 105 is a connection box having flexible conductors leading to and connecting with the solenoids 43 upon the frames 29 and 31 and with a commutator connection to a heater unit in the heating and drying roller 26.

Upon the opposite side member 17 of the carrier, similar flexible conductors connect the solenoids 43 and the measuring unit 102 with the source of electrical current.

A further detailed description of the operation of the apparatus will be best understood when considered in connection with a detailed description of the electrical hook up shown in the diagram of Figure 11. Referring therefore to the said diagram, the reference numeral 111 designates one side or line of the main circuit and is common to all circuits while 112 indicates the opposite side or line of same. 113 is a switch in the main supply line. All of the switches, except 113, in the diagram are shown, by full heavy lines, in their normal position just before the operation of the apparatus is started. With the carrier 13 in the starting position shown by the full lines in Figure 1 and the main switch 113 closed an electric current flow is established which runs from the main line 111 to branch line 114, through motor 56, line 115, across contact or switch closing member 116, line 117 to solenoid 118, line 119 across contact members 120 and 121, line 122, across contact 123, line 124, across contact 125 and line 126 to the main line 112 thereby completing a circuit which actuates the motor 56 to move the carrier forward. As the carrier starts its forward movement its action releases the contact member 125 and breaks the circuit at that point. To anticipate this break, however, the solenoid 118 which had been electrically energized draws and holds the contact to the position shown by the broken line 127 thereby holding the circuit closed and directing the current from line 117 and solenoid 118 through the line 128 to main line 112.

When the carrier reaches the end of its forward movement it trips a mechanism which breaks the circuit by moving the contact 116 to the position shown by the broken line 129, stops the motor 56 and closes a second circuit at that point. The course of this second circuit is through the main line 111, line 130 to the motor 67, line 131 across contact 132, line 133, solenoid 134, line 135, across contact 136, line 137, across contact 138, line 139 to contact 129 and line 140 to main line 112, thus completing the second circuit which actuates the motor 67 to move the printing bed 57 downwardly to its lowered position. When the

said printing bed reaches its lowermost position it contacts a mechanism which breaks the said second circuit at 132 by moving the said contact 132 to the position shown by the broken line 141 and thereby closes a third circuit to actuate a motor 82 which operates the inking roller mechanisms. This third circuit starts at the main line 141, runs through the motor 82, line 142, across contact 143, line 144, solenoid 145, line 146, across contact 147, line 148, across contact 141, line 149, line 150 across contact 151 and line 152 to the main line 112 thereby completing the third circuit which starts the motor 82 to drive the inking mechanism into the apparatus and over the printing plates 70 upon the printing bed 57. As the printing mechanism starts its movement forward its action allows the contact 147 to move inwardly to the position shown by the broken line 153 and breaks the circuit at 147. Anticipating this break, the solenoid 145 which is electrically energized draws the contact 136 to the position shown by the broken line 154 to keep the said third circuit closed until the said inking mechanism reaches the end of its movement and breaks the third circuit at 143 and moves the said contact 143 to the position shown by the broken line 155 thereby stopping the motor 82.

When the contact 155 closes the line at the point indicated a fourth circuit is established which beginning at the main line 111 runs through the motor 82, line 156, across contact 153, line 157, to solenoid 158, line 159, across contact 155 and through branch lines 155' and 155'' to main line 112 thus completing the fourth circuit which reverses the rotation of the motor to retract the inking mechanism. As the inking mechanism starts its retracting movement the contact 155 moves to 143 breaking the circuit at 155. The solenoid 158, however being electrically energized draws down the contact 138 to the position indicated by the broken line 160 and maintains the said fourth circuit closed until the printing mechanism is fully retracted and breaks the circuit at 153 to stop the motor 82.

The movement of the contact 147 also operates a snap switch 161, a fraction of a second before it closes the open circuit at 147, and sets up a fifth circuit to reverse the motor 56 and retract the carrier 13. This fifth circuit leads from the main line 111, to branch line 114, through motor 56, line 162, across contact 163 (the present position of contact 125), line 164, line 165, solenoid 166, line 167, solenoid 168, line 169, snap switch 161, line 170 and line 171 to main line 112 completing the fifth circuit to reverse the motor 56 and retract the carrier. The snap switch 161 acts momentarily to energize the solenoid 168 to draw down the contact 151 and holding the circuit closed by bringing the branch line 172 into the circuit and keeping said fifth circuit closed until the carrier is fully retracted.

At the end of its retracting movement the carrier brings the contact 125 back to its original position shown by the heavy line but, a fraction of a second before contact is made at 125, a snap switch is engaged to set up a circuit to reverse the rotation of the motor 67 and bring the printing bed 57 back to its upper level. This current flow runs from the main line 111, through branch line 130, motor 67, line 174, across the contact 175 (dotted line), line 176, solenoid 177, line 178, snap switch 173, and line 179 to main line 112 energizing the solenoid 177 to hold down the contact 121 as indicated by the broken line 180 whereupon the current flow is diverted along the

line 181 to the main line 112. This sixth circuit is held closed until the printing bed is fully raised whereupon this circuit is broken at contact 175 and closed at 182, stopping the motor 67 and bringing the printing bed 57 to rest at its upper working level.

The closing of the contact at 182 sets up a seventh circuit which actuates the solenoids 43 to release the fabric locking wedge clamps 38 and 39 as has been heretofore described, and then, almost simultaneously, actuates the motor 101 which winds up the fabric upon the roll 28. The current flow through this seventh circuit passes from the main line 111, through line 184, across contact 126, through line 185, line 186, to solenoids 43, through said solenoids, line 187, across contact 182 and along line 188 to main line 112 thereby completing the said seventh circuit which actuated the solenoids 43 to release the fabric 20. At the same time one of the said solenoids closes a branch circuit at 189 thereby establishing a current flow from line 187 through line 190, across contact 189 which is now in the position indicated by the dotted line 189, from the contact the flow is through line 191, across contact 192, line 193, solenoid 194, line 195, line 185, across contact 126, and along line 184 to main line 112 thereby completing the said seventh circuit and energizing the solenoid 194 to move the contact 123 to the position shown by broken line 196 and close a circuit which runs from the main line 111, through branch lines 114 and 197, through motor 101, line 198, across contact 196, and along line 199 to main line 112 thus completing a circuit which actuates the motor 101 and turns the wind up roller 28. The circuit which energizes the solenoid 194 is controlled by an adjustable cam 200 and follower 201 adapted to "make" and "break" the said circuit at the contact 192 and the said cam 200 is motivated by a measuring device 102 geared to the heater roller 26 as heretofore described. The action of the electrically energized solenoid 194 also serves to break the circuit at the contact 123 preventing the operation of the motor 56 to drive the carrier forward at this time. When the cam 200 and its follower 201 breaks the circuit at the contact 192, the circuit to the motor 101 is also broken at 196 and the circuit to operate the motor 56 is reestablished to restart the complete cycle of operation just described.

A motor 87 which is employed to give continuous rotation to the ink rollers 77 is supplied with electrical current by the lines 202, 203, 204 and 205 and needs no further explanation except that it operates independently of all other circuits and may be provided with a switch (not shown) to stop its operation if so desired.

A heater element which may be an electrical resistance unit 206 or a series of infra-red units is located within the heater roller 26 and is electrically energized by a current flow through line 202 from the main line 111, through lines 207, 208 and 205 to the main line 112 and it also may be supplied with an individual cut out switch (not shown) so that same may be independently controlled.

After the circuit passing through the solenoid 194 is broken by the action of the cam 200 and the forward drive for the carrier is started the said solenoid circuit is also broken at the contact 126. At this point a second cam 209, concentric with or operatively connected with the cam 200 closes a circuit by moving a contact 210 to the position shown by the broken line 211 momen-

tarly directing a circuit from the main line 112, along line 212, across contact 211, along line 213 to line 198 through motor 101, line 197, and line 114 to main line 111, thereby turning the motor 101 a short distance or far enough to reset the contact 192. The contact 211 being then released to stop the motor 101.

The switches, solenoids or relays are of a regulation type, at present obtainable in the market, and the wiring is standard. The hook up however, may vary and that shown herewith is but one arrangement of units to accomplish the result desired.

We claim:

- 15 1. In an apparatus for printing multicolor designs upon sheet material, a supporting frame, a vertically reciprocating printing bed thereon, a series of printing plates upon the said printing bed, a carrier reciprocally movable upon said supporting frame, rollers mounted upon said carrier adapted to carry and guide a sheet of material through the carrier, a pair of rollers mounted in vertically and reciprocally movable sliding frames upon said carrier, a means upon the carrier coordinating with the said sliding frame to hold same normally in its uppermost position, a second pair of rollers mounted in a second sliding frame vertically and reciprocally movable upon said carrier, a flexible supporting band connecting both said sliding frames and engaging over a pulley upon said carrier and adapted to move said sliding frames in unison, an impression roller upon the carrier, the said sheet material adapted to engage partly around said impression roller and partly around and between the said first and second pair of rollers mounted upon said sliding frames, means for locking the said sheet material between the said pairs of rollers, means for moving the said carrier to roll the sheet material, in consecutive order, over said series of printing plates, means for retracting the sheet material after having roller contact with each successive printing plate during the movement of the carrier, inking rollers reciprocally movable over said printing beds to ink the said printing plates carried thereon, means for registering the said sheet material as the said impression roller contacts each successive printing plate, automatically operated means for locking and releasing the sheet material and means for moving same to bring a succeeding section of the sheet material into line for printing.
- 20 2. The apparatus for printing multicolor designs upon sheet material as set forth in claim 1 wherein electrically operated means are provided for moving the said inking rollers over the said printing plates and retracting same after the said printing plates are inked.
- 25 3. The apparatus for printing multicolor designs upon sheet material as set forth in claim 1, wherein electrically operated means are provided whereby the said printing bed carrying the printing plates is lowered to allow said inking rollers to move over same, and means for raising the said printing bed after the said printing plates have been inked and the inking rollers have been retracted.
- 30 4. The apparatus for printing multicolor designs upon sheet material as set forth in claim 1 including a trough, upon said reciprocating carrier, containing a chemical coating fluid, a cylindrical brush rotatable upon said carrier and engaging said fluid in trough to apply said chemical fluid to the surface of said sheet material, a guide roller to hold the said sheet material in

contact with said cylindrical brush and means to rotate said guide roller and cylindrical brush for chemically coating the printing surface of the said sheet material.

5. The apparatus for printing multicolor designs upon sheet material as set forth in claim 1, including a means for measuring the sheet material as it moves intermittently through the paired rollers upon said vertically and reciprocally moving sliding frames.

6. The apparatus for printing multicolor designs upon sheet material as set forth in claim 1, including ink troughs and ink distributing rollers operating therein for supplying ink to the said inking rollers.

7. In an apparatus for printing multicolor designs upon sheet material as set forth in claim 1, including means for lifting the said ink rollers as they pass over the side of the said supporting frame inking mechanism and inking roller, for inking the said printing plates, means for lowering the said printing plates, means for lifting the said inking roller during part of its movement.

8. An apparatus for printing multicolor designs upon sheet material, comprising a supporting frame, a printing bed vertically and reciprocally movable in said supporting frame, a series of printing plates upon the said printing bed, a carrier reciprocally movable upon said supporting frame and carrying upon it sheet material a series of printing plates upon the said printing bed, an impression roller upon said reciprocally moving carrier, the said impression roller adapted to engage and guide the said sheet material into rolling contact over said series of printing plates to receive color impressions therefrom, inking rollers pivotally attached upon a block, reciprocally sliding upon said supporting frame and adapted to ink the said printing plates, ink trays and rollers for supplying variously colored inks to said inking rollers, means for intermittently moving a section of the sheet material upon the carrier as each preceding section of said sheet material has been imprinted and means to successively move, in the following order, the said carrier forward, lower the said printing bed, move the said inking rollers in from the side to and upon said printing plates, retract the said inking rollers, retract said carrier, raise the said printing bed and move a section of the said sheet material to bring a succeeding section of same into position for printing.

9. An apparatus for printing multicolor designs upon sheet material as set forth in claim 8 wherein wedge-shaped locking members engaging with said guide rollers upon said sliding frames to alternately lock and release said sheet material and solenoids upon said sliding frames to actuate said wedge locking members to hold or release, at predetermined intervals, the said sheet material are provided for intermittently locking and releasing the said sheet material.

10. An apparatus for printing multicolor designs upon sheet material as set forth in claim 8, including a trough, containing a chemical fluid, mounted in said carrier, a rotary brush engaging fluid in said trough and means for rotating said brush to apply a chemical coating to the printing surface of said sheet material with a chemical fluid.

11. The apparatus for printing multicolor designs upon sheet material as set forth in claim 8, wherein an impression roller is provided upon said carrier and is adapted to roll the said sheet material into contact with the said printing plates and wherein strap elements are provided upon the edges of said printing plates to give frictional contact to the said impression roller as it presses the said sheet material upon said printing plates.

12. The apparatus for printing multicolor designs upon sheet material as set forth in claim 8, wherein a measuring unit is provided for measuring the sheet material as each section of same is moved for succeeding printings.

13. The apparatus for printing multicolor designs upon sheet material as set forth in claim 8, wherein means are provided to release the sheet material after same receives an imprint from each successive printing plate.

14. An apparatus for printing multicolor designs upon sheet material as defined in claim 8, including an electrically driven motor, coacting with connecting gears and drive shaft to impart reciprocal motion to the said reciprocating carrier, a motor and coacting gears to raise and lower said printing bed, a motor to give reciprocal motion to the said inking rollers, a motor to intermittently motivate the said sheet material through the machine, a series of electrical circuits having intercommunicating connections with the said motors, said circuits having switches automatically controlled by the successive action of the reciprocating printing bed, reciprocating inking rollers and supplementary switches in the circuits.

ALFONSO BENAVIDES.
ULLA PERS.
